US00D966958S

(12) **United States Design Patent** (10) **Patent No.:** **US D966,958 S**
Gander (45) **Date of Patent:** **** Oct. 18, 2022**

(54) **GRILLE ELEMENT**(71) Applicant: **Oshkosh Corporation**, Oshkosh, WI (US)(72) Inventor: **Jesse Gander**, Larsen, WI (US)(73) Assignee: **Oshkosh Corporation**, Oshkosh, WI (US)(***) Term: **15 Years**(21) Appl. No.: **29/802,904**(22) Filed: **Aug. 9, 2021****Related U.S. Application Data**

(63) Continuation of application No. 29/750,416, filed on Sep. 14, 2020, now Pat. No. Des. 929,913, which is a continuation of application No. 29/729,772, filed on Mar. 30, 2020, now Pat. No. Des. 898,632, which is a continuation of application No. 29/706,526, filed on Sep. 20, 2019, now Pat. No. Des. 892,002, which is a continuation of application No. 29/691,172, filed on May 14, 2019, now Pat. No. Des. 863,144, which is a continuation of application No. 29/621,906, filed on Oct. 12, 2017, now Pat. No. Des. 856,860, which is a continuation of application No. 15/599,174, filed on May 18, 2017, now Pat. No. 10,434,995, which is a continuation of application No. 14/724,279, filed on May 28, 2015, now Pat. No. 9,656,640, said application No. 29/621,906 is a continuation of application No. 14/612,100, filed on Feb. 2, 2015, now Pat. No. 9,829,282, said application No. 14/724,279 is a continuation of application No. 13/841,686, filed on Mar. 15, 2013, now Pat. No. 9,045,014, said application No. 14/612,100 is a continuation of application No. 13/629,009, filed on Sep. 27, 2012, now Pat. No. 8,943,946.

(60) Provisional application No. 61/615,812, filed on Mar. 26, 2012, provisional application No. 61/539,838, filed on Sep. 27, 2011.
